(57) CLAIM

The ornamental design for a cooling patch, as shown and described.

DESCRIPTION

FIG. 1 is a top perspective view of a cooling patch showing the claimed design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a top perspective view of a cooling patch showing the claimed design;

FIG. 10 is a bottom perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.

The shade lines in the figures show contour and not surface ornamentation.

FIGS. 9–16 are illustrated to show contrasting appearance. Areas of the cooling patch that appear in different shades of gray represent areas with contrasting appearances. No particular shade or hue is claimed.

1 Claim, 10 Drawing Sheets
